Specification of Letters Patent.

Patented Oct. 8, 1912.

Application filed June 24, 1912. Serial No. 705,660.

To all whom it may concern:

Be it known that I, GUSTAVE H. COQUEUGNIOT, a citizen of the United States, residing at Los Angeles, in the county of Los Angeles and State of California, have invented a certain new and useful Improvement in Copying Apparatus, of which the following is a specification.

My invention relates to a duplicating apparatus, and particularly to a photographic copying machine for making true copies of papers, pictures and the like, directly on paper.

One of the objects of this invention is to provide an apparatus in which the paper is exposed, developed and fixed, in consecutive operations, without necessitating manual handling of the paper.

Another object of this invention is to provide an apparatus in which the paper after development is automatically removed from the developing cylinder and delivered face down to the fixing bath.

With these and other objects in view, this invention consists of the features, details of construction and combination of parts described in connection with the accompanying drawings and then more particularly pointed out in the claims.

In the drawings, Figure 1, is a side elevation, partly in section, showing the photographing apparatus, the feed roll for the paper, and the developing cylinder. Fig. 2, is a section on lines 2—2, Fig. 1, looking in the direction of the arrow, and showing the developing cylinder, and actuating mechanism for clamping the paper. Fig. 3, is a fragmentary section on lines 3—3, Fig. 2, showing the operating mechanism for the release of the paper from the developing cylinder. Fig. 4, is a segregated, perspective view, showing the operating mechanism for the clamping and releasing of the paper, the means for removing the paper from the cylinder, and the operating means for the removing means. Fig. 5, is a side elevation showing the position of the paper removing means, when the paper is clamped on the cylinder. Fig. 6, is a similar view showing the paper clamped in the cylinder and held clamped during development, and Fig. 7, is a side elevation showing the operative position of the means for removing the paper from the cylinder, and in dotted

lines, the position of the clamping means for the paper, after the release of the same.

Referring to the drawings, 1, designates a casing, in the upper part of which is journaled a flanged roller 2, for a roll of sensitized paper 3, arranged to be fed to the exposure chamber 4, of said casing, provided with photographic bellows 5, and lens 6, by rollers 7. In said exposure chamber 4, are two spaced plates 8, and 9, the former being an ordinary transparent glass plate, while the latter is a ground glass plate on which the focus of the object from the lens is made. These plates 8, and 9, serve also to guide the paper through the opening 10, in said exposure chamber 4, and to bring the end 11, of the paper in proper position for clamping and developing, by means presently described, after the same has been sheared off, by a preferably rotary knife 12, disposed on the top of said casing 1, and below said feeding rollers 7. In the lower part of said casing 1, and in an axial line with the opening 10, in said exposure chamber 4, is a cylinder 13, mounted on a shaft 14, journaled on one end in a bearing 15, integral with said casing, and having its other end extending through a sleeve 16, which is journaled in a bearing 17, integral with said casing. Said cylinder 13, is provided with a longitudinal groove 18, in which is disposed an oscillable bar 19, mounted in plates 20 and 21, secured to the ends of said cylinder. Said bar is provided with lugs 22, which, when the bar 19, is oscillated, clamp the end of the paper against the wall 23, of said longitudinal groove 18, and hold said paper clamped during the revolution by a crank 24, pinned on said shaft 14, of said cylinder, in a developing solution in a tray 25, supported in proper relation to said cylinder. The said wall 23, of the groove 18, is provided with projections 26, forming supports for the end of the paper, to prevent it from sliding under the clamp bar 19. On one end of said clamp bar 19, is fixed an arm 27, clearly shown in Fig. 4, provided with a pin 28, disposed in a cam slot 29, of a disk 30, which is integral with said sleeve 16. Connected with said sleeve 16, which is loosely mounted on said shaft 14, and located on the outside of said casing 1, is a knurled nut 31, by means of which the sleeve 16, and consequently the disk 30, is oscillated rela-

tively to the said shaft and cylinder, to control the opening and closing movement of said clamp bar 19. The crank 24, is held rigid during the movement of said nut 31, by any suitable means, as a bifurcation 32, hingedly secured to the casing 1. As seen in Fig. 4, the clamp bar 19, has been oscillated to bring the lugs 22, away from the wall 23, of the groove 18, in the cylinder 1, the pin 28, on the arm 27, occupying the position substantially as shown in said figure. When the disk 30, is oscillated in the direction of the arrow, Fig. 4, the cam slot 29, will cause an oscillation of said clamp bar 19, which thereupon clamps the end of the paper in the cylinder 13, the position of the parts then being substantially as shown in Fig. 5. The disk 30 and cylinder 13, are now connected, and the crank operated to revolve the cylinder, with the paper thereon in the developing solution in the tray 25.

When the cylinder has been revolved for a sufficient length of time to develop the paper, the clamp bar 19, is operated to release the end of the paper, which is then delivered face down to the fixing solution in the tray 32, fitting in the bottom of said casing. This is accomplished by the following mechanism: Loosely mounted in a rabbet of said bearing 17, is a disk 33, provided in the periphery thereof with a segmental notch 34, one wall 35, of which is curved, and the other of which is inclined, as seen at 36, for purposes to appear more fully hereinafter. On the side of said disk 33, is an abutment 37, arranged in a direct line with a stud 38, projecting through a cam slot 39, in said aforementioned disk 30. This stud is secured to the end of an arm 40, pivotally mounted on the side of said cylinder 13. Fulcrumed in said casing by a pin 41, is a lever 42, whose upper end is provided with a roller 43, arranged to slide over the periphery of said disk 33, and out of said notch 34, and whose lower end is furnished with an elongated slot 44, in which the pin 45, of a link 46, keyed on a rod 47, is arranged to operate. On said rod are a plurality of fingers 48, for removing the developed paper from said cylinder and delivering it to the fixing bath in the following manner.

When the disk 30, is oscillated by the nut 31, in the direction of the arrow, Fig. 4, the cam slot 29, in the disk 30, causes the clamp bar 19, to oscillate, and clamp the end of the paper, as shown in Fig. 5. Simultaneously the pin 38, projecting through the cam slot 39, is thrown out to a greater radius than that in which the abutment 37, on the disk 33, lies, and consequently passes over the said abutment during the revolution of the cylinder 13, in the direction of the arrow, Fig. 4. During this time, the fingers 48, on the rod 47, are in substantially the position illustrated in Figs. 4, 5 and 6, and the roller 43,

on the end of the lever 42, is in the segmental notch 34, of the disk 33. When the disk 30, is oscillated by the nut 31, in a direction opposite to the arrow shown in Fig. 4, the projecting pin 38, on the arm 40, will be brought within the same radius as that of the abutment 37, on the disk 33. As the cylinder 13, and disk 30, are revolved, by the crank 24, this pin 38, engages the said abutment 37, and moves the disk 33, with it, causing the roller 43, to ride over the inclined face 36, of the notch 34, and onto the periphery of the disk 33, as shown in Fig. 7. Such movement of the roller 43, onto the periphery of the disk 33, causes the lever 42, to operate the link 46, which, transmitting motion to the rod 47, carries the fingers 48, into the transverse grooves 49, in the cylinder and under the paper. When said roller 43, drops into the notch 34, of said disk 33, the fingers 48, now under the developed paper, gravitate to the position shown in Figs. 4, 5 and 6, and in so doing, carry with them and deliver the paper to the fixing bath. The aforementioned curved wall 35, of said segmental notch 34, is provided for the purpose of preventing the pin 38, from revolving the disk 33, in a direction opposite from that indicated by the arrow in Fig. 4, such curved wall 35, preventing the escape of said roller 43, from said notch 34.

What I claim is:—

1. The combination with a photographic casing having a roll of sensitized paper in the upper part thereof, of a plurality of plates to guide said paper, a developing cylinder journaled in the bottom of said casing, and provided with a longitudinal groove, a bar in said groove provided with lugs to engage the end of said paper and clamp it in said cylinder, means to operate said clamping means, a fixing tray in said casing, means to remove the paper from said cylinder and deliver it to said fixing tray, a disk to control said removing means, means to control said disk, and means movable in one direction to operate said clamping means and hold said removing means inoperative, and in the opposite direction to release said clamping means, and actuate said removing means.

2. The combination with a photographic casing having in the upper part thereof a roll of sensitized paper, of a cylinder having a longitudinal groove, a bar operable in said groove and provided with lugs to engage the end of said paper, a shaft on which said cylinder is mounted, a sleeve on said shaft provided with a disk for operating said clamp bar, means to operate said sleeve independently of said shaft, means to automatically remove the paper from said cylinder, a loosely mounted disk to control said removing means, means controllable by the oscillation of said clamp bar controlling disk in

one direction to cause said disk to travel with said sleeve, means to automatically control said paper removing means, and a crank to revolve said cylinder.

5 3. In a photographic copying apparatus, the combination with a casing having in the upper part thereof a roll of sensitized paper, of a cylinder journaled in said casing and provided with a longitudinal groove, a bar 10 in said groove to clamp the end of said paper, means to operate said bar, means to remove the paper from said cylinder, a disk to operate said removing means, means to operate said disk, and means to control both 15 said bar and said disk operating means.

4. In a photographic copying apparatus, the combination with a casing having in the upper part thereof a roll of sensitized paper, of a developing cylinder for an exposed 20 piece of paper, provided with a longitudinal groove, a bar in said groove to clamp the end of said paper, means to operate said bar, a shaft on which said cylinder is mounted, means to remove the paper from said cylinder, a disk to control said removing means, means to operate said disk, a sleeve loose on 25 said shaft and provided with a disk to operate said clamp bar and said disk operating

means, and means to move said sleeve independently of said shaft.

30

5. The combination with a casing having a roll of sensitized paper in the upper part thereof, of a developing cylinder, having a longitudinal groove, a shaft on which said cylinder is mounted, a crank to revolve said 35 cylinder, a sleeve loosely mounted on said shaft and forming a bearing for one end thereof, a cam disk on said sleeve, an automatic paper removing means in operative relation to said cylinder, a disk loosely mounted relatively to said sleeve to control said removing means, a paper clamping means in said groove, means operatively connected with said cam disk to operate said clamping means, means operatively connected with 40 said cam disk to actuate said disk for controlling said removing means, and means to actuate said sleeve independently of said shaft.
